CRANKSHAFT GRINDING MACHINE

Raymond A. Cole and Franklin E. Johnson,
Worcester, Mass., assignors to Norton Company,
Worcester, Mass., a corporation of Massachusetts

Application July 15, 1941, Serial No. 402,466

18 Claims. (Cl. 51—3)

The invention relates to grinding machines, and more particularly to a machine for grinding the crankpins of an automotive crankshaft.

One object of the invention is to provide a simple and thoroughly practical, readily controllable crankpin grinding machine. Another object of the invention is to provide a crankpin grinding machine having a multiplicity of grinding wheels which are arranged simultaneously to grind spaced aligned crankpins on a crankshaft. Another object of the invention is to provide a multiple wheel crankpin grinding machine with a hydraulically operated control mechanism whereby a plurality of grinding wheels may be indexed longitudinally and fed transversely simultaneously to grind a plurality of pins on a crankshaft.

A further object of the invention is to provide a fluid pressure interlock between the wheel feed control and the wheel indexing or traversing mechanism whereby the wheels cannot be indexed longitudinally until the grinding wheels are in their rearward or inoperative position. A further object of the invention is to provide such a hydraulic interlock which is operative to actuate a switch to stop the work rotation during the longitudinal traversing or indexing movement of the grinding wheels. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of a crankpin grinding machine embodying the invention;

Fig. 2 is a right-hand end elevation, on an enlarged scale, of the crankpin grinding machine as shown in Fig. 1;

Fig. 3 is a hydraulic diagrammatic illustration of a portion of the fluid pressure system, showing the traversing mechanism for the wheel slides;

Fig. 4 is a combined electric wiring diagram and fragmentary hydraulic diagram, showing the work stop control mechanism together with the grinding wheel indexing and feeding mechanism and the steady-rest actuating mechanism;

Fig. 5 is a fragmentary sectional view, taken approximately on the line 5—5 of Fig. 2, through

the manually operable wheel feed adjusting mechanism;

Fig. 6 is a fragmentary rear elevation, on an enlarged scale of the hydraulic interlock mechanism;

Fig. 7 is a fragmentary horizontal sectional view, taken approximately on the line 7—7 of Fig. 1, through the vertically movable steadyrest;

Fig. 8 is a fragmentary sectional view, on an enlarged scale taken approximately on the line 8—8 of Fig. 1, through the control lever;

Fig. 9 is a fragmentary cross sectional view, on an enlarged scale, taken approximately on the line 9—9 of Fig. 4, through one of the control valves;

Fig. 10 is a diagrammatic illustration of a modified hydraulic system in which a single piston and cylinder mechanism serves simultaneously to index two spaced grinding wheels; and

Fig. 11 is a fragmentary cross sectional view, taken approximately on the line 11—11 of Fig. 10.

A double head crankpin grinding machine has been illustrated in the drawings comprising a base 20 which serves as a support for a pair of spaced transversely movable wheel slides 21 and 22 carrying grindings wheels 23 and 24, respectively. The grinding wheels 23 and 24 are supported on wheel spindles 25 (only one of which has been shown in Fig. 2 of the drawings). The wheel spindles 25 are journaled in suitable bearings in the wheel slides 21 and 22, respectively. The wheel slide 21 is supported by a V-way 26 and a flat way 27 and the wheel slide 22 is supported by a V-way 28 and a flat way 29 so that they may be fed transversely to produce the desired grinding action.

The grinding wheels 23 and 24 together with their supporting wheel slides 21 and 22 are preferably arranged so that they may be indexed or traversed longitudinally successively to position the grinding wheels in operative positions to grind successive pairs of aligned crankpins on a crankshaft 30 to be ground. As shown in Fig. 1, the grinding wheels 23 and 24 are positioned and arranged to grind a pair of aligned crankpins 31 and 32 on the crankshaft 30. After the pins 31 and 32 have been ground to the required and predetermined size, the crankshaft 30 is rotarily indexed to position a pair of pins 33 and 34 in alignment so that the crankshaft 30 rotates about the axis of the pins 33 and 34, after which the grinding wheels 23 and 24 together with their supporting slides 21 and 22, respectively, are simultaneously indexed toward each other into operative position in alignment with the second

pair of pins 33 and 34 to grind the same to the required and predetermined size. Similarly, after the pins 33 and 34 have been ground, the crankshaft 30 is again rotarily indexed to position the crankshaft so that it rotates about the axis of a pair of aligned pins 35 and 36. The wheels 23 and 24 together with their supporting slides 21 and 22 are then again indexed toward each other into alignment with the pins 35 and 36 so that these pins may be ground to the desired and predetermined size.

In order to provide for a longitudinal indexing of the grinding wheels 23 and 24, the wheel slides 21 and 22 are mounted on longitudinally traversable slides or carriages 37 and 38, respectively. The V-way 26 and flat way 27 on the slide 21 mate with correspondingly shaped ways on the upper surface of the longitudinally movable slide 37. Similarly, the V-way 28 and flat way 29 on the wheel slide 22 mate with correspondingly shaped ways on the upper surface of the longitudinally movable slide 38. The longitudinally movable slide 38 is supported by a V-way 39 and a flat way 40 on correspondingly shaped ways formed on the upper surface of the base 20 so that the slide 38 together with the wheel slide 22 and the grinding wheel 24 may be indexed or traversed longitudinally to position the grinding wheel 24 in the desired relationship with the portions of the work piece to be ground. The longitudinally movable slide 37 is similarly provided with a V-way and flat way (not shown) which correspond to the V-way 39 and flat way 40, by means of which the slide 37 together with the wheel slide 21 and the grinding wheel 23 may be indexed or traversed longitudinally to position the grinding wheel 23 in the desired and predetermined relationship with portions on the work piece 30 to be ground.

Grinding wheel drive

The grinding wheels 23 and 24 may be rotated by independent motor drives including electric motors 42 and 43 which are adjustably mounted on the wheel slides 21 and 22, respectively. The electric motors 42 and 43 are each provided with a driving pulley 44 and 45, respectively. These pulleys are of a multiple V-groove type which are connected by multiple V-belts 46 and 47 with corresponding multiple V-groove pulleys 48 and 49 (only one of which is shown in Fig. 2) which are mounted on the outer ends of the wheel spindles 25. The electric motors 42 and 43 are started and stopped by push button switches 73 and 74, respectively.

A fluid pressure wheel feeding mechanism is provided to control the feeding movement and adjustment of the grinding wheels toward and from the crankshaft 30 to be ground. Independent feed controlling mechanisms are provided for each of the wheel slides 21 and 22, respectively, so that each wheel may be fed independently of the other wheel. In the preferred construction, however, the two controlling mechanisms are arranged so that the grinding wheels may be fed simultaneously into grinding contact with the work piece to be ground by means of a control mechanism to be hereinafter described. The wheel slide 21 is provided with a depending half nut 50 which meshes with a rotatable feed screw 51. The feed screw 51 is rotatably supported in bearings in the longitudinally movable slide 37. The feed screw 51 may be rotated manually for adjusting the wheel slide 21 in setting up the ma-

chine by a manually operable feeding mechanism to be hereinafter described.

In order that the wheel slide 21 may be rapidly moved toward and from the crankshaft 30 to grind the crankpins thereon by the plunge-cut method, the feed screw 51 is connected to a piston rod 52. A fluid pressure cylinder 53 is arranged in axial alignment with the feed screw 51 and contains a slidably mounted piston 54 which is connected to or formed integral with the piston rod 52. A fluid pressure pump 55 (Fig. 3) is mounted to be driven by an electric motor 56 which may be started and stopped by a push button switch 41 (Fig. 1) located on the left-hand end of the machine. The pump 55 is arranged to force fluid under pressure through a pipe 57 from a reservoir 58 within the base 20. The pump 55 forces fluid under pressure through the pipe 57 to a valve chamber 59 in a feed control valve 60. The feed control valve 60 is a piston type valve comprising a valve stem 61 having valve pistons 62, 63, 64, 65 and 66 formed integral therewith.

In the position of the valve 60 (Fig. 4), fluid under pressure entering the valve chamber 59 located between the valve pistons 63 and 64 passes outwardly through a pipe 67 into a cylinder chamber 68 to cause the piston 54 to move rearwardly so as to move the wheel slide 21 and the grinding wheel 23 to its rearward or inoperative position away from the crankshaft 30 being ground. During the passage of fluid into the cylinder chamber 68, fluid is exhausted from a cylinder chamber 69, through a pipe 70, into a valve chamber 71 located between the valve pistons 62 and 63, and out through a pipe 72 which exhausts into the reservoir 58. The exhaust from the control valve 60 passes through two valves in the pipe 72 which can be adjusted to throttle the exhaust to control the hydraulic functioning of the various elements of the machine connected to the control valve 60.

A manually operable control lever 75 is pivotally mounted on a stud 76 which is in turn carried by a bracket 77 mounted on the front of the machine base 20. The lever 75 is operatively connected by means of a pin 78 with the valve stem 61 by means of which movement of the lever 75 serves to move the valve stem 61 in either direction, depending upon the direction of movement of the lever 75. When it is desired to cause an infeeding movement of the grinding wheel 23, the control lever 75 is moved in a counterclockwise direction (Fig. 4) to move the valve stem 61 downwardly, which movement serves to cause fluid under pressure entering the valve chamber 59 to pass outwardly through the pipe 70 into the cylinder chamber 69 to move the piston 54 and the feed screw 51 to cause a forward feeding movement of the wheel slide 21 and the grinding wheel 23. Similarly, a fluid pressure wheel feeding mechanism is provided to control the feeding movement and adjustment of the wheel slide 22. The wheel slide 22 is provided with a depending half nut 80 (Fig. 2) which meshes with a rotatable feed screw 81. The feed screw 81 is rotatably supported in bearings in the longitudinally movable slide 38. The feed screw 81 may be rotated manually for adjusting the position of the wheel slide 22 in setting up the machine by a manually operable feeding mechanism to be hereinafter described.

In order that the wheel slide 22 may be rapidly moved toward and from the crankshaft 30 to be ground, to grind crankpins thereon by the

plunge-cut method, the feed screw 81 is connected to a piston rod 82. A fluid pressure cylinder 83 is arranged in axial alignment with the feed screw 81 and contains a slidably mounted piston 84 which is connected to or formed integral with the piston rod 82. A fluid pressure pump 85 is preferably formed as a tandem or duplex pump combined with the pump 55 and is driven by the electric motor 56. The pump 85 forces fluid under pressure through a pipe 86 from the reservoir 58 within the machine base 20. The pump 85 forces fluid under pressure through the pipe 86 into a valve chamber 87 of a feed control valve 88. The valve 88 is preferably a piston type valve comprising a valve stem 89 having formed integrally therewith valve pistons 90, 91, 92, 93 and 94.

In the position of the valve 88 (Fig. 4), fluid under pressure entering the valve chamber 87 passes outwardly through a pipe 88 into a cylinder chamber 96 to cause the piston 84 to move rearwardly to withdraw the wheel slide 22 and the grinding wheel 24 to a rearward or inoperative position away from the crankpins of the crankshaft 30 being ground. During the passage of fluid under pressure into cylinder chamber 96 to cause a rearward movement of the piston 84, fluid is exhausted from a cylinder chamber 97, through a pipe 98, into a valve chamber 99 located between the valve pistons 90 and 91, and out through a pipe 100 which exhausts into the reservoir 58. The exhaust from the control valve 88 passes through two valves in the pipe 100 which can be adjusted in the same manner as valves in the exhaust pipe 12, as previously described.

A control lever 105 is pivotally mounted on a stud 106 carried by a bracket 107 on the front of the machine base. The control lever 105 is connected by means of a stud 108 with the valve stem 89 by means of which the control lever 105 may be actuated to shift the valve stem 89 as desired to cause either a rearward or forward feeding movement of the grinding wheel 24 and wheel slide 22. When it is desired to cause a forward feeding movement of the grinding wheel 24, the control lever 105 is moved in a clockwise direction (Fig. 4) so that fluid under pressure entering the valve chamber 87 passes outwardly through the pipe 88 into the cylinder chamber 97 to cause a forward movement of the piston 84 to move the wheel slide 22 and grinding wheel 24 forward into an operative position to grind a crankpin on the shaft 30.

A fluid pressure connection is provided between the feed control valves 80 and 88. A pipe 110 is connected between the pipe 87 and a manually operable valve 111. A pipe 112 is connected between the valve 111 and a cylinder chamber 113 at the forward end of the feed control valve 88. In the position of the valve 111 (Fig. 4), the valve chamber 113 is connected through the valve 111 and a pipe 114 with the exhaust pipe 100.

Similarly, the forward movement of the valve stem 89 of the feed control valve 88 may be hydraulically controlled by the feed control valve 80. A pipe 101 is connected between the pipe 78 and a manually operable valve 102. A pipe 103 is connected between the valve 102 and a cylinder chamber at the rearward end of the feed control valve 88, this chamber being similar to the chamber 113 at the forward end. In this position of the valve 111 (Fig. 4), the rearward end chamber is connected, through the valve 102 and a pipe 104, with the pipe 114 which is con-

nected with the exhaust pipe 100 and the exhaust pipe 12 to the reservoir 58.

If it is desired that the feed control valve 60 hydraulically actuate the rearward movement of the feed control valve 88, the manually operable valve 111 is actuated so that pipe 110 will be connected to pipe 112 and the valve 102 will remain in the position shown in Fig. 4. When the control lever 15 is actuated to move the feed control valve 60 forward, the pipe 67 is connected with the exhaust, also the pipe 110. Consequently the control lever 105 may move the valve stem 89 forward since the fluid in the cylinder chamber 113 is not under pressure but exhausts through the pipe 112, valve 111, and the pipes 110 and 67. When the grinding wheels 23 and 24 have sparked out so that grinding is completed, the control lever 15 is moved rearwardly and the feed control valve 60 will admit pressure to the pipe 67 to move the grinding wheel 23 to an inoperative position. When the pipes 67 and 110 are connected to pressure, fluid under pressure passing therethrough moves the valve stem 89 rearwardly, admitting pressure to the pipe 95 to move the grinding wheel 24 to an inoperative position.

If it is desired to have the feed control valve 60 hydraulically actuate the forward movement of the valve stem 89 of the feed control valve 88 without the operator touching the control lever 105 and to have the operator manually control the rearward movement of the valve stem 89, this may be accomplished by turning the manually operable valve 102 so that the pipe 101 will be connected to the pipe 103 and the valve 111 will remain in the position shown in Fig. 4. This setting of the valves 102 and 111 is opposite to the setting previously described. Therefore, when the control lever 15 moves the valve stem 61 of the feed control valve 60 forward, the pipe 70 is connected to pressure to move the grinding wheel 23 forward and at the same time pressure through the pipe 101, valve 102 and the pipe 103 moves the valve stem 89 forward, admitting pressure to the pipe 98 to move the grinding wheel 24 forward into engagement with the aligned crankpins for a grinding cycle.

Dash pot

The piston and cylinder mechanisms above described serve to cause the grinding wheels 23 and 24 together with their supporting wheel slides 21 and 22, respectively, rapidly to approach or recede from the crankshaft 30 to be ground. In order to reduce the rapid approaching movement to a predetermined grinding feed, it is desirable to provide a fluid pressure controlling mechanism, such as a dash pot mechanism, which may be rendered effective when the grinding wheels 23 and 24 are about to contact with the surface of the crankpins to be ground. As illustrated in Fig. 4, the cylinder 53 is provided with a casing 115 which contains a pair of diametrically opposed dash pot pistons 116 and 117 which slide within dash pot cylinders 118 and 119. The dash pot pistons 116 and 117 are normally held in rearward positions by springs 120 and 121, respectively. During the rapid approaching movement of the grinding wheel 23, the dash pot pistons 116 and 117 are ineffective. The piston rod 52 extends toward the rear of the machine and is provided at its rear end with a sleeve 122 which may be adjusted longitudinally 75 on a threaded portion 123 of the piston rod 52

and locked in adjusted position by a lock nut 124. The parts are so arranged that the sleeve 122 moves rearwardly when the piston 84 moves into a rearward position.

The dash pot pistons 116 and 117 are limited in their rearward movement by adjusting screws 125 and 126, respectively. When fluid under pressure is admitted to the cylinder chamber 69 to cause the grinding wheel 23 to move toward the crankshaft 30, the rapid approaching movement continues until the end of the sleeve 122 engages the ends of the dash pot pistons 116 and 117, after which continued movement of the piston 84 is retarded by the dash pot pistons 116 and 117 which force fluid under pressure from the dash pot chambers through a needle valve 127 into a reservoir 128.

Similarly, a casing 135 is fixedly mounted on the end of the cylinder 83 and contains a pair of diametrically opposed dash pot pistons 136 and 137 which slide within dash pot cylinders 138 and 139, respectively. The dash pot pistons 136 and 137 are normally held in a rearward position by springs 140 and 141, respectively. During the rapid approaching movement of the grinding wheel 24, the dash pot pistons 136 and 137 are ineffective. The piston rod 82 extends toward the rear of the machine and is provided at its rearward end with an adjustable sleeve 142 which may be adjusted longitudinally on a threaded portion 143 of the piston rod 82 and locked in adjusted position by means of a lock nut 144. The parts are so arranged that the sleeve 142 moves rearwardly when the piston 84 moves into a rearward position. The dash pot pistons 136 and 137 are limited in their rearward movement by means of adjusting screws 145 and 146, respectively.

When fluid under pressure is admitted to the cylinder chamber 97 to cause the grinding wheel 24 to move toward the crankshaft 30, the rapid approaching movement continues until the end of the sleeve 142 engages the ends of the dash pot pistons 136 and 137, after which continued movement of the piston 84 is retarded by the dash pot pistons 136 and 137 which force fluid under pressure from the dash pot chambers through a needle valve 147 into a reservoir 148. By regulation of the needle valves 127 and 147, respectively, the rate of grinding feed may be readily adjusted as desired.

Positive stop

In order to grind a work piece to a predetermined size, it is necessary to feed the grinding wheel toward the crankpins of the crankshaft 30 and then stop the infeed and allow the grinding wheel to grind out or allow the sparks to die out in order to round up the work so that it will be ground to a true cylindrical surface of a predetermined size. As illustrated in Fig. 2, the forward movement of the piston rod 82 causes a rapid approach until the sleeve 122 picks up the dash pot pistons 116 and 117 to cause a slow grinding infeed which continues until an adjustable stop sleeve 150 engages a fixed end surface 151 on the rear face of the dash pot casing 115, thereby limiting the infeeding movement of the grinding wheel 23 and the wheel slide 21 to cause a dwell of the wheel in contact with the work during a finish grinding period. The adjustable stop sleeve 150 surrounds the sleeve 122 and is threaded thereto by means of a thread 152 and held in adjusted position thereon by means of a lock nut 153.

An identical mechanism is provided on the rear end of the cylinder 83 for slowing down and stopping the infeeding movement of the grinding wheel 24 and its supporting slide 22. This mechanism comprises an adjustable stop sleeve 155 which surrounds the sleeve 142 and is arranged to engage a stop surface 156 formed on the rear surface of the dash pot casing 135. The sleeve 155 is threaded onto a threaded portion 157 on the periphery of the sleeve 142 and is arranged to be held in adjusted position thereon by means of a lock nut 158.

Manual feed adjustment

Each of the feed screws 51 and 81 are arranged so that they may be manually rotated independently to adjust the position of the wheel slides 21 and 22 when desired. The feed screw 51 is provided at its forward end with a bevel gear 160 which meshes with a bevel gear 161 mounted on the inner end of a rotatable shaft 162. The outer end of the shaft 162 carries a gear 163 meshing with a gear 164 carried by a rotatable shaft 165 which also supports a manually operable feed wheel 166.

The feed screw 81 may be rotated manually by a similar manually operable feed mechanism comprising a bevel gear 170 which meshes with a bevel gear 171 carried on the inner end of a rotatable shaft 172. The shaft 172 supports a gear 173 which meshes with a gear 174 on a shaft 175. A manually operable hand wheel 176 is mounted on the outer end of the shaft 175.

To facilitate adjusting the feed screws from the operator's station in front of the machine, either during a truing operation or to compensate for wheel wear, an electrically controlled mechanism is provided automatically and incrementally to advance the wheels 23 and 24, respectively, by desired and predetermined increments. This mechanism is substantially the same as that disclosed in the prior U. S. patent to Wallace H. Wood and Carl G. Flygare, No. 2,151,669 dated March 21, 1939, to which reference may be had for details of description not contained herein.

The feed screw 51 may be automatically adjusted from the front of the machine by means of a pawl and ratchet mechanism comprising a ratchet wheel 178 mounted on the hand wheel 166 and a pair of pawls 179. The pawls 179 are mounted on one arm of a bell crank lever 180 which is actuated by means of a fluid operated piston 181 which is slidably mounted within a cylinder 182. A control valve 183 serves to control the admission of fluid to the cylinder 182 and a solenoid 184 is provided for actuating the valve 183. A push button 185 is provided on the front of the machine base whereby the solenoid 184 may be energized when desired to rotate the feed screw 51 by a desired and predetermined amount incrementally to adjust the position of the grinding wheel 23. The extent of movement of the feed pawls 179 is controlled by a pair of opposed adjusting screws 186 and 187 which are arranged in the path of an arm 188 formed integral with the bell crank lever 180.

Similarly, the feed screw 81 may be adjusted from the control station in front of the machine by means of a ratchet wheel 190 mounted on the hand wheel 176 (Fig. 5). The ratchet pawls 191 are carried by one arm of a bell crank lever 192 which is rocked by means of a piston 193. The piston 193 is slidably mounted within a cylinder 194. A control valve 195 serves to control the

admission of fluid to the cylinder 184. A solenoid 186 is provided for actuating the valve 185. A push button switch 197 is mounted adjacent to the operator's control station whereby the solenoid 186 may be readily actuated to provide the desired incremental feeding movement of the screw 81 for adjusting the position of the grinding wheel 24 and its supporting slide 22 to compensate for wheel wear or during a truing operation. A pair of opposed adjusting screws 198 and 199 are provided to facilitate adjustment of the stroke of the pawls 181. These adjusting screws are mounted on opposite sides of an arm 200 which is formed integral with or fixedly mounted to the bell crank lever 192. A snap switch 201 (Fig. 1) is provided, by means of which both grinding wheels 23 and 24 may be incrementally fed simultaneously by actuation of either of the push button switches 185 and 197. It will be readily apparent from the foregoing disclosure that by means of the remote electrical control above described, both the grinding wheel 23 and the grinding wheel 24 may be adjusted by one or more increments when desired from the operator's control station in front of the machine.

The longitudinally movable slides 37 and 38 are provided with power operated indexing or traversing mechanisms which in the preferred form are hydraulically operated. A cylinder 205 mounted on the base 20 of the machine contains a slidably mounted piston 206. The piston 206 is connected by means of a piston rod 207 with a bracket 208 which is fastened to the left-hand end of the slide 37. The admission to and exhaust of fluid from the cylinder 205 is controlled by a control valve 209 which will be hereinafter described. A similar mechanism is provided for controlling the indexing or traversing movement of the longitudinally movable slide 38, comprising a cylinder 215 which contains a slidably mounted piston 216. The piston 216 is connected by means of a piston rod 217 with a bracket 218 which is fixedly mounted on the right-hand end of the slide 38. The admission and exhaust of fluid from the cylinder 215 is controlled by a control valve 219 which will be hereinafter described.

Work support

The crankshaft 30 to be ground is rotatably supported by a pair of spaced aligned work heads 220 and 221 which are provided at their inner ends with rotatably mounted pot chucks 222 and 223, respectively. These pot chucks 222 and 223 are fixedly mounted on the ends of a pair of aligned rotatable spindles which are journaled in suitable bearings (not shown) within the heads 220 and 221, respectively. The details of disclosure of the spindle construction have not been illustrated since this feature is not considered to be a part of the present invention and since the structure thereof is substantially identical to that shown in the prior U. S. patent to Herbert A. Silven, No. 2,151,666 dated March 21, 1939, and U. S. patent to Herbert A. Silven, and Albert G. Belden, No. 1,837,342 dated February 22, 1931, to which reference may be had for details of disclosure not contained herein.

The pot chucks 222 and 223 are driven by sprockets 224 and 225 which are mounted on the outer ends of the rotatable work spindles. The sprockets 224 and 225 are connected by link chains 226 and 227, respectively, with sprockets 228 and 229, respectively, which are in turn supported on opposite ends of a rotatable drive shaft 75

230. The drive shaft 230 is journaled in suitable bearings within the base of the machine.

A driving mechanism is provided comprising an electric motor 231 which is supported on the base of the machine. The electric motor 231 is connected by a multiple V-belt 232 with a pulley 233. The pulley 233 is supported on a rotatably mounted shaft 234 having a sprocket 235 mounted thereon. The sprocket 235 is connected by a link chain 236 with a sprocket 237 which is mounted on the driving shaft 230. It will be readily apparent from the foregoing disclosure that rotary motion of the work driving motor 231 will be transmitted through the driving mechanism previously described synchronously to rotate the pot chucks 222 and 223 uniformly to drive and rotate the opposite ends of the crankshaft 30 to be ground.

In a crankshaft grinding machine of the type illustrated, it is desirable to stop the pot chucks 222 and 223 in upright positions to facilitate the loading operation. A motor brake switch 240 is provided for stopping the motor 231 at the desired and predetermined time to stop the pot chucks. The motor brake switch 240 is controlled by a cam 241 and a normally closed trip switch 242.

When the valve 60 is shifted to its rearward position, a cam surface on a cross-shaped head 333 opens the normally closed limit switch 334 to break the circuit. Similarly when the valve 88 is shifted to its rearward position, a cam surface on a cross-shaped head 343 opens the normally closed limit switch 344 to break the circuit. The two limit switches 334 and 344 are preferably connected in parallel so that it is necessary for both grinding wheels to be in an inoperative position before the work holders 222 and 223 may be automatically stopped in a predetermined loading position. When the circuit through the limit switches 334 and 344 is broken, a solenoid 238 on the work head 220 is deenergized to release the tension of a spring. This movement serves to rock a lever 239 into the position shown in Figs. 2 and 4, to move a slidably mounted rod 243 so that a roller on the end of the rod rides upon the periphery of a cam 241. The cam 241 is mounted on a sleeve (Fig. 4) to rotate with the work supporting spindle.

The motor 231 for rotating the work supporting pot chucks 222 and 223 is preferably of a type which is controlled by a magnetic reverse starter switch and a motor brake switch 240 so that the rotation of the motor 231 may be stopped in a predetermined position after a grinding operation has been completed. As shown in the electrical diagram (Fig. 4), the motor 231 is controlled by a magnetic starter reverse relay 244 which controls the forward and reverse fields of the motor 231.

When the solenoid 238 is deenergized, the roller mounted on the rod 243 is moved by the spring actuated lever 239 into contact with the cam 241. The movement of the roller on the rod 243 into operative contact with the cam 241 serves to open a normally closed trip switch 242 which opens the circuit and cuts the power from the power field of the motor 231. This movement serves through the motor brake switch 240 to actuate a magnetic motor reverse relay 258 which serves instantaneously to reverse the current in the motor 231 and, through the motor brake switch 240, to stop the motor 231 so that the work holders 222 and 223 are in predetermined positions.

A safety relay 258 is so connected as to render the power circuit inoperative in case the electric

current fails. Upon failure of the electric current supplied to the driving motor 231, the safety relay 259 opens and before the work rotation can be again started, a make contact reset push button 280 must be pushed to close the circuit. This movement in turn serves to close the safety relay 244 and thereby again start the rotation of the motor 231. A make contact push button 281 serves as a jogging switch to jog the rotation of the work if desired. A double pole snap switch 282 serves in one position to permit a jogging of the work rotation by the push button 281 or in the opposite position shown in Fig. 4 serves to start the rotation of the motor 231. A double pole snap switch 283 serves in one position to render the automatic control of the work rotation inoperative to facilitate manual control to permit jogging of the work rotation as desired, and in the position shown in Fig. 4 serves to render the automatic control of the work rotation operative. By manipulation of the push buttons 280 and 281 and the snap switches 282 and 283, the rotation of the work drive motor 231 may be readily controlled as desired. A relay 284 serves to control the use of the motor brake switch 240 by braking the circuit through one of the contacts in the starter reverse relay 244 which controls the motor reverse relay 258.

It is not deemed necessary to fully describe the work stop control mechanism in the present case since this feature is not considered to be a part of the present invention and since the mechanism is substantially identical with that shown in the prior U. S. Patent to Herbert A. Silven, No. 2,151,666 dated March 21, 1939, to which reference may be had for details of disclosure not found herein.

A push button switch 280 (Figs. 1 and 4) is provided for controlling the starting and resetting of the work drive motor 231. The pot chucks 222 and 223 are spring clamped and hydraulically released, as is shown in the prior patent to Silven above mentioned. A cylinder 245 mounted on the left-hand end of the machine (Figs. 1 and 4) contains a slidably mounted piston 246 which is journaled to one end of a piston rod 247 the other end of which is connected to release the clamping action of the pot chuck 222 at the left-hand end of the crankshaft 30.

A cylinder 248 is mounted on the right-hand end of the machine and contains a slidably mounted piston 249 which is journaled to one end of a piston rod 250. The other end of the piston rod 250 is connected to release the clamping action of the pot chuck 223 on the right-hand end of the crankshaft 30. The cylinder 245 contains a cylinder chamber 251 which is connected by means of a pipe 252 with a pipe 253 which is connected with the control valve 88. The cylinder 248 contains a cylinder chamber 254 which is connected by a pipe 255 which connects with the pipe 253.

From this construction it will be readily apparent that fluid under pressure passing through the pipe 253 will be simultaneously admitted to the cylinder chambers 251 and 254 simultaneously to release the clamping action of the pot chucks 222 and 223 after a grinding operation has been completed. A pipe 256 is connected between the control valve 60 and the control valve 88 so that fluid under pressure cannot be passed through the pipe 253 to unclamp the work until both the control valve 60 and the control valve 88 are in their rearward positions to move the grinding wheels 23 and 24 to their rearward or inoperative

positions. In the position shown in Fig. 4, fluid under pressure from the pump entering the valve chamber 59 passes through a pipe or passage 257 and through a valve chamber located between the valve pistons 65 and 66 (Fig. 9), through the pipe 256, to the control valve 88, through a valve chamber located between the valve pistons 93 and 94, and outwardly through the pipe 253 and simultaneously through the pipes 252 and 255 to move the pistons 246 and 249 into the positions illustrated in Fig. 4 to unclamp both of the pot chucks 222 and 223. The connection between the pipes 256 and 257, when the valve chamber between the valve pistons 65 and 66 is aligned with the pipes for fluid pressure, is directly opposite port holes (Fig. 9). The construction is the same in the other feed control valve.

Steadyrest

In the grinding of a crankshaft or any long cylindrical work piece, it is desirable to provide a work steadyng rest to steady the work and prevent vibration thereof during the grinding operation. In the grinding of heavy objects, such as crankshafts, it is desirable that the steadyrest be arranged so that it is out of the way during the loading of a crankshaft into the machine and the removal of the finished shaft therefrom. In the preferred construction, a pair of steadyrests 260 and 261 are provided for simultaneously steadyng opposed aligned crankpins on the crankshaft 30 during simultaneous grinding thereon. The steadyrests 260 and 261 are preferably arranged so that they may be moved vertically to and from an operative position to facilitate traversing or indexing the rests by and in timed relation with the indexing or traversing of the grinding wheels 23 and 24, respectively.

The steadyrest 260 is provided with a transversely adjustable steadyrest shoe 262. The transversely movable shoe 262 is supported on a vertically movable slide 263. A fluid pressure mechanism is provided for moving the steadyrest shoe 262 and the slide 263 vertically to and from an operative position, comprising a fluid pressure cylinder 264 having a slidably mounted piston 265 which is connected to one end of a piston rod 266. The lower end of the piston rod 266 is operatively connected to the vertically movable slide 263 so that when fluid under pressure is admitted to the cylinder chamber below the piston 265, the slide 263 together with the steadyrest shoe 262 will be moved vertically into an operative position.

It is desirable that the steadyrest shoe 262 engage, support and steady the crankpin being ground, and that the steadyrest be indexed longitudinally to position it successively in operative relation with successive crankpins on the shaft 30. The fluid pressure cylinder 264 is preferably formed as an integral part of a steadyrest frame. The steadyrest frame is provided with two slide-ways which mate with correspondingly shaped slide-ways 267 and 268 on the upper surface of the base 20 (Fig. 2). The frame of the steadyrest 260 has an integral rearwardly extending portion 269 (Fig. 10) which is fixedly fastened to the longitudinally movable slide 37 by means of which the steadyrest 260 may be traversed or indexed by and in timed relation with the longitudinally movable slide 37 when the grinding wheel 23 and its supporting wheel slide 21 are indexed longitudinally into operative position with relation to successive crankpins on the crankshaft 30 to be ground.

Similarly, the steadyrest 261 (Figs. 1, 2 and 4) is provided with a transversely adjustable steadyrest shoe 278 which is carried by a vertically movable slide 271 (Fig. 7). The slide 271 is moved in a vertical direction by a fluid pressure cylinder 272 which has a slidably mounted piston 273 contained therein. The piston 273 is connected to the upper end of a piston rod 274, the lower end of which is fixedly connected to the vertically movable slide 271. The cylinder 272 is formed integral with the frame of the steadyrest 261. The frame of the steadyrest 261 is provided with slideways mating with the slideways 287 and 288 (Fig. 2) and has an integral rearwardly extending portion 297 which is fastened to the longitudinally movable slide 38 so that the steadyrest 261 will be indexed or traversed longitudinally by and in timed relation with the indexing movement of the grinding wheel 24 as it is successively indexed for grinding pins on the crank-shaft 38.

It is desirable that the steadyrest shoe 262 be moved into operative engagement with the work 38 in timed relationship with the movement of the grinding wheel 24 toward an operative position. A pipe 275 is connected between the pipe 87 and a cylinder chamber 277 in the cylinder 284 so that when fluid under pressure is admitted to cause a rearward movement of the grinding wheel 24, fluid under pressure will be simultaneously admitted to the upper cylinder chamber 277 to move the steadyrest 260 downwardly to an inoperative position. A pipe 276 connects the cylinder chamber below the piston 285 with a valve chamber located between the valve pistons 62 and 63 and in the position of the control valve 68 (Fig. 4) fluid exhausts therefrom through the pipe 72. It will be readily apparent from the foregoing disclosure that when the valve 68 is shifted to admit fluid under pressure through the pipe 78, fluid under pressure will also be passed through the pipe 276 to raise the steadyrest 260 to an operative position.

The steadyrest 261 is similarly hydraulically connected with the control valve 88. A pipe 278 is connected with the pipe 88 so that when fluid under pressure is admitted through the pipe 88 to cause a rearward movement of the grinding wheel 24, fluid will be simultaneously passed through the pipe 278 into the upper cylinder chamber 279 of the cylinder 272 to cause the piston 273 to move downwardly into the position illustrated in Fig. 4, moving the steadyrest to an inoperative position. A pipe 298 is connected between the lower cylinder chamber of the cylinder 272 and a valve chamber 88 located between the valve pistons 88 and 81 of the control valve 88. In the position of the valve 88 (Fig. 4) fluid exhausting through the pipe 298 into the valve chamber 88 will exhaust through the pipe 100 into the reservoir 58. When the control valve 88 is moved to admit fluid under pressure through the pipe 88 to cause a forward feeding movement of the grinding wheel 24, fluid under pressure is passed through the pipe 298 to cause the piston 273 together with the steadyrest 261 to move upwardly into an operative position.

Wheel index control

The control valve 288 is a piston type valve which is manually controlled by a knob 285. Fluid under pressure from the pump 55 passes through the pipe 87 and through a pipe 288 into a valve chamber 287. When it is desired to index the grinding wheel 24 toward the right, the 70 75

control knob 285 is moved toward the right so that fluid under pressure entering the valve chamber 287 passes outwardly through a pipe 288 which, in the position of the parts illustrated, 5 by-passes through a by-pass valve 289, through a pipe 290, and into a cylinder chamber 291 to move the piston 296 and the slide 31 together with the grinding wheel 24 toward the right. During the movement of the piston 296 toward the right, fluid within a cylinder chamber 292 exhausts through a pipe 293, through a valve chamber in the control valve 288, and out through an adjustable throttle valve 294 and adjustable valve 295 and a pipe 296 to the reservoir 58.

Similarly, if it is desired to index the wheel 24 toward the left, the knob 285 is moved toward the left so that fluid under pressure entering the valve chamber 287 passes through the pipe 288 into the cylinder chamber 292 to move the piston 296 and the slide 31 together with the grinding wheel 24 toward the left. During the movement of the piston 296 toward the left, fluid exhausts from the cylinder chamber 291, through the pipe 290, the by-pass valve 289, the pipe 288, to a valve chamber in the control valve 288, and out through an adjustable throttle valve 294 and valve 295 which connects with the exhaust pipe 296 into the reservoir 58. By adjusting the throttle valves 294, 296 and 298, the speed of indexing movement of the grinding wheel 24 may be independently adjusted.

The traversing or indexing movement of the grinding wheel 24 is controlled in a similar manner by the control valve 219 which is actuated by a knob 300. Fluid under pressure from the pump 55 passing through the pipe 86 passes through a pipe 301 into a valve chamber 302. When it is desired to index the grinding wheel 24 toward the left, the control knob 300 is moved toward the left so that fluid under pressure entering the valve chamber 302 passes out through a pipe 303 to the by-pass valve 289, through a pipe 304, into a cylinder chamber 305 to move the piston 216 and grinding wheel 24 toward the left. During the movement of the piston 216 toward the left, fluid within a cylinder chamber 306 exhausts through a pipe 307 to the control valve 219, passes through a valve chamber in the central valve 218, and through an adjustable throttle valve 308, adjustable valve 315, and an exhaust pipe 309 into the reservoir 58.

Similarly, if it is desired to index the grinding wheel 24 toward the right, the knob 300 is moved toward the right so that fluid within the valve chamber 302 passes outwardly through the pipe 307 into the cylinder chamber 306. During this movement, fluid within the cylinder chamber 305 passes through the pipe 304, through the by-pass valve 289, the pipe 303, to the control valve 219, through a valve chamber in the control valve 219, and through an adjustable throttle valve 310 and adjustable valve 318 and an exhaust pipe 309 into reservoir 58. It will be readily apparent from the foregoing disclosure that by manipulation of the throttle valves 308, 309 and 315, the speed of the indexing movement of the grinding wheel 24 may be independently varied in its movement in either direction. Spring-pressed detents 311 and 312 are provided to engage notches 313 and 314 when the control valves 288 and 219 are in a central or neutral position.

By-pass valve

The by-pass valve 289 is a normally closed valve in which a spring 316 normally holds a valve

piston 317 in its left-hand position (Fig. 3). When fluid under pressure is passed through the pipe 253 (Fig. 4) and simultaneously through pipe 255 the pot chucks 222 and 223, respectively, are unclamped after a grinding operation has been completed. Fluid under pressure also passes through a valve 320, through an adjustable throttle valve 321, into a valve chamber 322, to move the piston 317 into the position illustrated in Fig. 3, in which position fluid may readily by-pass between the pipes 303 and 304 and between the pipes 288 and 290, thus rendering the longitudinal wheel indexing mechanism operative so that the grinding wheels 23 and 24 may then be indexed longitudinally to position them for grinding the next pair of aligned pins on the crankshaft 30.

In case it is desired to render the by-pass valve 289 inoperative, the valve 320 may be turned to the opposite position (Fig. 3), in which position fluid under pressure is admitted through an extension of the pipe 57 to move the piston 317 to the right, as shown, so that fluid may flow freely at all times into the cylinders 205 and 215. A pipe 323 is connected between the pipes 288 and 290. A pipe 324 is connected between the pipes 303 and 304. The pipes 323 and 324 are shunted around the by-pass valve 289 and each pipe has an adjustable valve which is normally shut off, but when the valve 320 is turned to direct pressure, the valves in the pipes may be opened to shorten the passage of fluid. If desired, the valve 320 may remain as shown in Fig. 3 and the valves in the pipes 323 and 324 may be opened to shunt fluid around the by-pass valve 289.

Interlock

It is desirable to provide a fluid interlock between the transverse feeding and the longitudinal indexing movements of the grinding wheels so that the grinding wheels cannot be indexed longitudinally until the wheel feed control valves have been shifted to cause a movement of the grinding wheels to a rearward or inoperative position. The interlock mechanism is also provided with an electrical interconnection whereby the work drive motor 231 is stopped by and in timed relation with the movement of the feed control valves 60 and 88 to a position to cause a rearward movement of the grinding wheels 23 and 24, respectively. The hydraulic interlock comprises a plurality of parallel fluid pressure cylinders 325, 326, 327 and 328 which are arranged around the periphery of the rear end of the control valve 60 (Fig. 6). The cylinders 325, 326, 327 and 328 contain slidably mounted pistons 329, 330, 331 and 332, respectively. All of the pistons are fixedly connected to the cross-shaped head 333 which is fixedly attached to the rear end of the valve stem 61.

The limit switch 334 is mounted in fixed relationship with the valve 60 and is arranged so that it is actuated by the cross head 333 when it moves to a rearward position. The switch 334 is a normally closed switch which is opened when the cross head 333 moves to its rearward position to break the circuit so as to stop the rotation of the work drive motor 231.

Similarly, a plurality of fluid pressure cylinders 335, 336, 337 and 338 are symmetrically arranged around the peripheral rear end of the control valve 88. Slidably mounted pistons 339, 340, 341 and 342 are slidably mounted in the cylinders 335, 336, 337 and 338, respectively. The ends of the pistons 339, 340, 341 and 342 are fixedly connected to the cross-shaped head 343 which is in

turn fixedly mounted on the rear end of the valve stem 89. The normally closed limit switch 344 is mounted in fixed relation with the control valve 88 and is arranged so that when the control valve 88 is moved toward a rearward position, the cross head 343 will engage the actuating plunger of the limit switch 344 and open the switch to break a circuit and thus stop the work drive motor 231. As previously described, both limit switches 334 and 344 must be open before the work drive motor 231 automatically stops.

The pipe 293, in addition to being connected with the cylinder chamber 292 of the wheel traversing or indexing cylinder 205, is operatively connected with the cylinders 325 and 335. The pipe 288 is similarly connected with the cylinders 326 and 336. The pipe 307 is connected with the cylinders 327 and 337 and the pipe 303 is connected with the cylinders 328 and 338.

The mechanism previously described serves as an interlock between the traversing mechanism for indexing the grinding wheels 23 and 24 longitudinally and is arranged so that if the traverse control valves 209 or 219 are shifted from neutral or central positions while the valves 60 and 88 are in a wheel feeding position, the passage of fluid through the pipes 288, 293, 303 or 307 will pass into the chambers of the cylinders 325, 326, 327, 328, 335, 336, 337 or 338 automatically to shift the feed control valves 60 and 88 to a rearmost position, which movement serves to admit fluid under pressure to cause the grinding wheels 23 and 24 together with their supporting wheel slides 21 and 22 to move rearwardly to an inoperative position. The wheels 23 or 24 cannot be indexed until the control valves 60 and 88 have been shifted to their rearward positions and fluid under pressure passed through the by-pass valve 289.

The by-pass valve 289 cuts off either the exhaust or pressure line to the cylinders 205 and 215 so that the pistons 206 and 216 cannot be moved until fluid under pressure passing through the pipe 253 enters the valve chamber 322 to move the by-pass valve 289 toward the right, thus allowing free passage through the pressure or exhaust lines so that the pistons 206 or 216 will transmit a longitudinal indexing movement to the grinding wheel 23 or 24. The adjustable throttle valve 321 interposed between the valve 320 and the chamber 322 serves to control the rate of passage of fluid into the chamber 322 so that the action of the by-pass valve may be adjusted to allow a sufficient time interval to elapse so that the grinding wheels 23 and 24 may move to their rearward position before a longitudinal indexing movement may be initiated. It will thus be seen that an interlock is provided between the mechanisms so that the traverse or index control valves cannot be accidentally shifted so as to start a traversing or indexing movement of the grinding wheels 23 and 24 when the wheels are in a forward or grinding position.

A pair of adjustable stop screws 350 and 351 are supported in a bracket 352 which is fixedly mounted on the base 20. The stop screws 350 and 351 are arranged in the path of the piston rods 207 and 217. When the pistons 206 and 216 are indexed toward each other to position the grinding wheels 23 and 24 for grinding the crank-pins 35 and 36 (Fig. 1), the stop screws 350 and 351 are engaged by the end face of the piston rods 207 and 217, respectively. By adjusting the screws 350 and 351, the position of the wheels 23 and 24 may be adjusted so as to align the wheels relative to the pins to be ground. Similarly, a

pair of adjustable stop screws 355 and 356 are supported in brackets 357 and 358 which are fixedly supported on the base 20. The stop screws 355 and 356 are arranged in the path of depending lugs 359 and 360 which depend from the brackets 208 and 218, respectively (Fig. 3). The stop screws 355 and 356 serve to limit the indexing movement of the wheels 23 and 24 as they are moved into the position illustrated in Fig. 1 while grinding the crankpins 31 and 32, respectively.

The grinding wheels 23 and 24 are indexed longitudinally under the control of the manually operable valves 209 and 218 which are actuated by the manually operable knobs 285 and 300, respectively. The wheels 23 and 24 are indexed longitudinally into position for grinding successively the pairs of crankpins 31-32, 33-34 and 35-36 by manual control of the valves 209 and 218.

Spark splitting device

The crankshaft to be ground on a crankpin grinding machine of this type is usually rough turned in a crankshaft lathe and the crankpins are not always located accurately in a longitudinal direction so that it is difficult to locate the grinding wheels by means of a sufficiently accurate indexing mechanism so that the grinding wheel will grind equally on opposite side cheeks of the crankpin at the start of the grinding operation. It is, therefore, desirable to provide a spark splitting or jogging device whereby the side grinding of the grinding wheels 23 and 24 during the grinding of the cheeks of a crankpin may be readily equalized. This mechanism has not been illustrated in detail since it is not considered to be a part of the present invention and since this mechanism is identical with that shown in the prior U. S. patent to Carl G. Flygare No. 2,101,794 dated December 27, 1937, and the patent to Herbert A. Silven No. 2,151,666 dated March 21, 1939, to which reference may be had for details of disclosure not contained herein. A manually operable lever 361 (Fig. 1) is mounted on the upper end of an oscillatable stud 362. The mechanism contained within the casing 363 and the wheel slide 21 is identical with that shown in the patent to Silven above referred to and is operatively connected to move the wheel spindle supporting the grinding wheel 23 in an axial direction as controlled by the movement of the spark-splitting lever 361.

A similar spark-splitting lever 364 (Fig. 2) is mounted on the upper end of an oscillatable shaft 365. A mechanism identical with the Silven construction is contained within the casing 366 and serves to move the wheel spindle axially within its bearings to position the grinding wheel 24 when the lever 364 is moved. As in the patent to Silven, when the grinding wheels 23 and 24 are moved toward a grinding position under the control of the valves 80 and 88, respectively, the spark-splitting levers 361 and 364, respectively, are moved so that the grinding wheels 23 and 24, respectively, grind equally on their side faces as the wheels move toward the crankpin.

Modification

A modified form of grinding wheel indexing mechanism has been illustrated in Figs. 10 and 11 in which a single fluid pressure operated cylinder 378 is provided for simultaneously indexing the grinding wheels 23 and 24 in opposite directions to position the wheels successively in the full line positions, into dot and dash positions 23a and 24a and into positions 23b and 24b, re-

spectively. The cylinder 378 is fixedly mounted relative to the base 20 and contains a slidably mounted piston 371. The piston 371 is connected to a piston rod 372. A rack bar 373 is connected to the left-hand end of the piston rod 372 (Fig. 10) and is slidably mounted in a shoe 374. The rack bar 373 meshes with a gear 375 which is formed integral with a shaft 376 (Figs. 10 and 11). The shaft 376 is rotatably journaled in a bearing 377 which is fixedly mounted relative to the base 20. A gear 378 is formed integral with the upper end of the shaft 376 and meshes with a pair of opposed rack bars 379 and 380, respectively. The rack bar 379 is fixedly mounted to the under side of the longitudinally movable slide 37 which carries the wheel slide 21, and the rack bar 380 is fixedly mounted to the under side of the longitudinally movable slide 38 which supports the transversely movable wheel slide 22. Guide blocks 381 and 382 are provided for slidably supporting the rack bars 379 and 380 to maintain them in operative mesh with the gear 378.

It will be readily apparent from the foregoing disclosure that when fluid is admitted through a pipe 383 into a cylinder chamber 384 to move the piston 371 toward the left (Fig. 10), this movement transmits a corresponding movement toward the left of the rack bar 373, which movement rotates the gear 375, the shaft 376 and the gear 378 in a clockwise direction, which movement causes the rack bars 379 and 380 to move longitudinally in opposite directions, that is, toward the left and toward the right, respectively, simultaneously to move the grinding wheels 23 and 24 longitudinally away from each other. Similarly, when fluid under pressure is admitted through a pipe 385 into a cylinder chamber at the left-hand end of the cylinder 378, it moves the piston 371 toward the right (Fig. 10) to transmit a corresponding movement toward the right of the rack bar 373. Movement of the rack bar 373 toward the right serves to cause a counterclockwise rotary movement of the gear 375, the shaft 376, and the gear 378, to move the rack bars 379 and 380 toward the right and toward the left, respectively, which transmits a longitudinal indexing movement of the wheels 23 and 24 to move them relatively toward each other into positions 23a and 24a for grinding the crankpins 33 and 34, respectively, and thereafter into positions 23b and 24b for grinding the crankpins 35 and 36, respectively.

A stop mechanism is provided for limiting the longitudinal indexing movement of the grinding wheels 23 and 24. A stop sleeve 388 is adjustably mounted on a threaded portion 389 of the piston rod 372. A lock nut 390 serves to hold the stop sleeve 388 in adjusted position. When the piston 371 is moved toward the left so that the stop sleeve 388 engages the end surface of the right cylinder head of the cylinder 378, the separating movement of the grinding wheels 23 and 24 is stopped in adjusted position for grinding the crankpins 31 and 32, respectively, of the crankshaft 30. Similarly, when the piston 371 is moved toward the right into its right-hand end position, a stop screw 392 carried by a bracket 393 which is fixed relative to the base 20 serves to limit a stop lug 394 which is fixedly mounted with respect to the rack bar 373. When the lug 394 engages the stop screw 392, it stops the movement of the piston 371 toward the right and locates the grinding wheels 23 and 24 in posi-

tions 23b and 24b for grinding the crankpins 35 and 36 on the crankshaft 38.

An electro-hydraulically operated mechanism is provided for stopping the grinding wheels 23 and 24 in positions 23a and 24a, respectively. A detent 395 having adjustable cam surface is fixedly mounted on the end of the threaded portion 389 of the piston rod 372 and is arranged to move in the path of an actuating plunger 396 of a normally open limit switch 397. The limit switch 397 is supported by a bracket 398 which is in turn fixedly supported relative to the base 20. When the detent 395 moves toward the right (Fig. 10), the cam face on the detent will engage and depress the actuating plunger 396 to close the limit switch 397 and stop the longitudinal indexing movement of the grinding wheels 23 and 24 in positions 23a and 24a, respectively.

A control valve 400 is provided for controlling the admission to and exhaust of fluid from the cylinder 370. This valve is a piston type valve which is controlled by a manually operable knob 401. The valve 400 is normally held in a central or neutral position by a compression spring 402. Fluid under pressure from the pump 85 passes through a pipe 403 into a centrally located valve chamber 404. When it is desired to index the grinding wheels 23 and 24, the knob 401 is shifted either toward the right or toward the left, depending upon the direction of movement it is desired to impart to the grinding wheels 23 and 24. When the knob 401 is moved toward the left, fluid under pressure passing into the valve chamber 404 passes out through a pipe 405 which connects with the pipe 385 to admit fluid under pressure to the cylinder chamber to the left of the piston 371 (Fig. 10) to move the piston toward the right, which movement causes a longitudinal indexing movement of the wheels 23 and 24 toward each other. During this movement, fluid exhausts from the cylinder chamber 384 through the pipe 383.

Similarly, when it is desired to index the grinding wheels 23 and 24 in the opposite direction, that is, away from each other, the knob 401 is moved toward the right so that fluid under pressure entering the valve chamber 404 passes outwardly through a pipe 406 which connects with the pipe 383 in a manner to be hereinafter described to pass fluid under pressure to the chamber 384 so as to move the piston 371 toward the left (Fig. 10). The valve 400 controls the adjustable fast and slow or truing speeds and is controlled and used in the same manner as the control valves 209 and 219 (Fig. 3).

A fluid pressure interlock is provided for interlocking the traversing mechanism with the wheel feeding mechanism in a manner similar to that described in connection with Figs. 3 and 4. A pair of cylinders 408 and 409 are arranged on diametrically opposite sides of the peripheral rear end of the control valve 60. Pistons 410 and 411 are slidably mounted within the cylinders 408 and 409. The pistons 410 and 411 are fixedly connected to a cross head 412 which is fastened to the rear end of the valve stem 61. A normally closed limit switch 413 is fixedly mounted so that its actuating plunger is in the path of a cam surface on the cross head 412 so that when the cross head is in a rearward position, the limit switch is opened to break the circuit and thus stop the rotation of the work. Similarly, a pair of cylinders 414 and 415 are arranged integrally on diametrically opposite

sides of the peripheral rear end portion of the control valve 88. Slidably mounted pistons 416 and 417 are contained within the cylinders 414 and 415. The upper ends of the pistons 416 and 417 are fixedly connected to a cross head 418 which is fixedly connected to the rear end of the valve stem 89 of the control valve 88. A normally closed limit switch 419 is fixedly mounted so that its actuating plunger is in the path of a cam surface on the cross head 418 so that when the cross head 418 moves to its rearward position, it opens the limit switch 419 to stop the work drive motor 231. As previously explained, both of the limit switches 413 and 419 in this modification must also be open before the work drive motor 231 automatically stops.

The pipe 405 is operatively connected to the cylinders 408 and 414 so that when fluid under pressure is passed through the pipes 405 and 385 to move the piston 371 toward the right, fluid will also be admitted to the cylinders 408 and 414 to move the pistons 410 and 416 together with the cross heads 412 and 418, respectively, toward a rearward position to shift the control valves 60 and 88 to a position to cause a rearward movement of the grinding wheels 23 and 24 to move them to an inoperative position. Similarly, the pipe 406 is connected to the cylinders 409 and 415, respectively, so that when fluid under pressure is passed through the pipes 406 and 383 to cause a movement of the piston 371 toward the left, fluid will be admitted to the cylinders 409 and 415 to shift the control valves 60 and 88 to move the wheels 23 and 24 to a rearward or inoperative position.

A by-pass valve 420 is provided between the pipes 406 and 383 which is arranged so as to delay the passage of fluid either to or from the cylinder 370 a sufficient length of time to make sure that the control valves 60 and 88 are shifted to move the grinding wheels 23 and 24 rearwardly to an inoperative position before the longitudinal traversing movement of the grinding wheels 23 and 24 may be started and also to make sure that the rotation of the work piece 30 is stopped before the indexing movement of the grinding wheels takes place. Fluid passing through the pipe 406 passes through an adjustable throttle valve 421 into a pair of cylinders 422 and 423 which are connected to move a valve stem 424 toward the right (Fig. 10) so as to shift the valve piston 425 against the compression of a spring 426 so that fluid under pressure may pass unrestricted between the pipes 383 and 406, respectively. By regulation of the valve 421, the speed of movement of the valve piston 425 may be varied as desired. It will be readily apparent from the foregoing disclosure that when the control valve 400 is shifted to produce a longitudinal indexing movement of the grinding wheels 23 and 24, such movement is delayed until the control valves 60 and 88 are moved to remove the grinding wheels to an inoperative position and to stop the work rotation before the longitudinal indexing movement takes place. The by-pass valve 420 operates on the pressure side of the system when fluid under pressure is passed through the pipe 406 to cause a movement of the piston 371 toward the left. Similarly, when fluid under pressure is passed through the pipe 405 to produce an indexing movement of the piston 371 toward the right, fluid under pressure in the pipe 405 passes through an adjustable throttle valve 426 to shift the valve piston 425 so as to allow exhaust of

fluid to flow through the by-pass valve 420 from the pipe 383 into the pipe 406.

An electrically controlled valve 428 is provided for stopping the grinding wheels 23 and 24 in positions 23a and 24a, respectively. When the detent 395 engages the limit switch plunger 396 to close the limit switch 397, it serves to close a circuit, thus energizing a solenoid 429 to move a spring retracted valve stem 430 toward the right (Fig. 10). In the position illustrated in Fig. 10, fluid exhausting from the valve 400 through a pipe 431 passes through a valve chamber located between valve pistons 432 and 433 and out through an exhaust pipe 434. When the solenoid 429 is energized to move the valve stem 430 toward the right, fluid under pressure exhausting from the pipe 431 enters a valve chamber located between the valve pistons 435 and 432 which in this position is not connected to the exhaust, thus cutting off the exhaust from the valve 400 and stopping the indexing movement of the grinding wheels in positions 23a and 24a, respectively.

An electrical control circuit is provided comprising power lines 436 which are connected to a stop and start push button switch 437 and a pair of break contact push button switches 438 and 439 which are conveniently located at the left and right ends of the base 20 relative to the operator's control station in front of the machine. These latter push buttons are connected in series with the limit switch 397 and the solenoid 329. After the crankpins 33 and 34 have been ground with the grinding wheels 23a and 24a, the indexing movement of the grinding wheels may be initiated by opening either the push button 438 or the push button 439 to break the circuit, thus deenergizing the solenoid 429, and at the same time to shift the control valve 400 while holding the push button switch open until the detent 395 rides over the plunger 396.

The control valve 400 is preferably located on the right-hand end of the front of the machine base 20. In order to facilitate control of the machine, a second control valve 440 is provided which may be located adjacent to the left-hand end on the front of the machine base. This valve 440 merely serves to convey fluid under pressure to an end chamber 441 or an end chamber 442 of the control valve 400 to shift it either in one direction or the other against the compression of the spring 402 so as to cause an indexing movement of the grinding wheels in a manner heretofore described. The function of the valve 440 is merely for the convenience of the operator so that indexing of the wheels may be controlled when the operator is adjacent to the left-hand end of the machine.

The operation of the machine will be readily apparent from the foregoing disclosure. A crankshaft 30 is placed in position in the pot chucks 222 and 223, after which the control levers 75 and 105 are shifted to shift the control valves 60 and 88. During the initial movement of the control valves 60 and 88, fluid under pressure within the clamp release cylinders 245 and 248 is exhausted, thus allowing the clamps to engage and clamp the work in position for grinding. The grinding wheels 23 and 24 are then moved to an operative position to grind the pins 31 and 32 simultaneously. As the wheels 23 and 24 approach the pins 31 and 32, the spark splitting levers 361 and 364 are manually adjusted by the operator to equalize the grinding on opposed sides of the grinding wheels 23 and 24.

After the grinding has been completed on the pins 31 and 32, the levers 75 and 105 are shifted to cause a rearward movement of the grinding wheels, after which the grinding wheels 23 and 24 may be indexed longitudinally to position them opposite the pins 33 and 34, respectively, in a manner hereinabove described. As the grinding wheels 23 and 24 move to their rearward or inoperative position, the work rotation is stopped and the work clamps released to facilitate indexing of the crankshafts 30 so as to position the crankpins 33 and 34 with their axes in alignment with the axis of rotation of the pot chucks 222 and 223. The control valves 60 and 88 are then shifted again so that the grinding wheels 23 and 24 simultaneously grind the pins 33 and 34.

After this grinding operation has been completed, the control valves 60 and 88 are again shifted to move the grinding wheels to an inoperative position and the wheels are then indexed longitudinally to positions 23b and 24b, respectively, after which the crankshaft 30 is again indexed to position the axis of the crankpins 35 and 36 in axial alignment with the axis of rotation of the pot chucks 222 and 223 to facilitate grinding of these pins.

After the completion of the grinding of the pins 35 and 36, the wheels are again moved to their rearward position to facilitate removal of the ground crankshaft and replacement thereof with a new crankshaft to be ground. On the grinding of the second crankshaft, the grinding wheels 23 and 24 may remain in their center positions adjacent to each other, that is, in positions 23b and 24b, to grind pins 35 and 36 on the next shaft, after which the wheels are indexed outwardly away from each other to grind successive pairs of pins. This cycle of operation may then be continued on successive crankshafts. It will be readily apparent from the foregoing disclosure that the grinding wheels 23 and 24 may be either indexed independently relative to each other in a manner shown in Figs. 3 and 4 or may be simultaneously indexed in a manner shown in the modification illustrated in Fig. 10.

The hydraulic system, including the grinding wheel indexing control valves and the grinding wheel feeding control valve, is so arranged that either grinding wheel unit may be operated independently to grind one or more portions on a work piece such as a crankshaft, or both grinding wheel units may be operated simultaneously to grind successively pairs of aligned spaced pins on a crankshaft.

It will thus be seen that there has been provided by this invention a grinding machine in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a grinding machine having a base, a rotatable work support including a pair of spaced work heads on said base, a pair of spaced rotatable grinding wheels, means simultaneously to feed said grinding wheels transversely simultaneously to grind a pair of aligned pins on a crankshaft, and means simultaneously to index

said grinding wheels longitudinally successively into alignment with successive pairs of pins on a crankshaft.

2. In a grinding machine having a base, a rotatable work support including a pair of spaced work heads on said base, a pair of spaced rotatable grinding wheels, means simultaneously to feed said grinding wheels transversely simultaneously to grind a pair of aligned pins on a crankshaft, and means simultaneously and automatically to index said grinding wheels longitudinally in opposite directions successively into alignment with successive pairs of pins on a crankshaft.

3. In a crankpin grinding machine having a base, a rotatable work support including a pair of spaced work heads on said base, a pair of spaced rotatable grinding wheels, means including an independent piston and cylinder to feed said grinding wheels transversely simultaneously to grind a pair of aligned crankpins on a crankshaft, and means including an independent piston and cylinder automatically to index said grinding wheels longitudinally and successively into alignment with successive pairs of pins on a crankshaft.

4. In a crankpin grinding machine having a base, a rotatable work support including a pair of spaced work heads on said base, a pair of spaced rotatable grinding wheels, means including an independent piston and cylinder to feed said grinding wheels transversely simultaneously to grind a pair of aligned crankpins on a crankshaft, and means including a piston and cylinder simultaneously and automatically to index said grinding wheels longitudinally in opposite directions successively in alignment with pairs of aligned crankpins on a crankshaft.

5. In a crankpin grinding machine having a base, a rotatable work support including a pair of spaced work heads on said base, a pair of spaced rotatable grinding wheels, means including a fluid pressure piston and cylinder mechanism to index said grinding wheels longitudinally, means including a pair of independent pistons and cylinders each of which is connected to feed one of said grinding wheels transversely simultaneously to grind a pair of aligned crankpins on a crankshaft, an independent manually operable control valve for each of said cylinders, and fluid connections including a valve connected between said control valves whereby fluid under pressure from one of said control valves serves to shift the other control valve.

6. In a crankpin grinding machine having a base, a rotatable work support including a pair of spaced work heads on said base, a pair of spaced rotatable grinding wheels, means including a fluid pressure piston and cylinder mechanism to index said grinding wheels longitudinally, means including a pair of independent pistons and cylinders each of which is connected to feed one of said grinding wheels transversely simultaneously to grind a pair of aligned crankpins on a crankshaft, an independent manually operable control valve for each of said cylinders, and fluid connections including a two-way valve connected between said control valves whereby fluid under pressure from one of said control valves serves to shift the other control valve, said fluid connections being arranged so that the second control valve may be moved in either or both directions by fluid under pressure from the first control valve.

7. In a grinding machine having a base, a ro-

tatable grinding wheel and a rotatable work support which are movable longitudinally and transversely relative to each other, a piston and cylinder transversely to feed said grinding wheel and work support relatively toward and from each other, a manually operable feed control valve therefor, a piston and cylinder longitudinally to traverse said grinding wheel and work support relative to each other, a manually operable traverse control valve therefor, and a fluid pressure interlock including a piston and cylinder operative to shift the feed control valve into a position to cause a transverse separating movement between the grinding wheel and work support before a longitudinal traversing movement may be initiated.

8. In a grinding machine having a base, a rotatable grinding wheel and a rotatable work support which are movable longitudinally and transversely relative to each other, a piston and cylinder transversely to feed said grinding wheel and work support relatively toward and from each other, a manually operable feed control valve therefor, a piston and cylinder longitudinally to traverse said grinding wheel and work support relative to each other, a manually operable traverse control valve therefor, a fluid pressure interlock including a piston and cylinder operative to shift the feed control valve, and fluid pressure connections between the traverse control valve and said interlock cylinder whereby the feed control valve is automatically shifted into a position to cause a transverse separating movement between the grinding wheel and work support before a longitudinal traversing movement may be initiated.

9. In a grinding machine having a base, a rotatable work support thereon, a longitudinally and transversely movable rotatable grinding wheel on said base, a piston and cylinder to feed said grinding wheel transversely, a manually operable control valve therefor, a piston and cylinder to traverse said grinding wheel longitudinally to position it relative to the work support, a manually operable control valve therefor, and a fluid pressure interlock between said valves to prevent a longitudinal traversing movement of the grinding wheel except when it is in an inoperative position.

10. In a grinding machine having a base, a rotatable work support thereon, a longitudinally and transversely movable rotatable grinding wheel on said base, a piston and cylinder to feed said grinding wheel transversely, a manually operable control valve therefor, a piston and cylinder to traverse said grinding wheel longitudinally to position it relative to the work support, a manually operable control valve therefor, and a fluid pressure interlock between said valves including a piston and cylinder operatively connected to move said feed control valve transversely to separate the grinding wheel and work support before a longitudinal traversing movement may be initiated.

11. In a crankpin grinding machine having a base, a rotatable work support including a pair of spaced work heads on said base to support a crankshaft, a pair of spaced rotatable grinding wheels, means simultaneously to feed said grinding wheels transversely simultaneously to grind aligned pins on the crankshaft, means simultaneously to index said grinding wheels longitudinally and successively into alignment with successive pairs of pins on a crankshaft, and an interlock whereby both of the grinding wheels

are automatically moved transversely to an inoperative position before either of the grinding wheels may be traversed longitudinally.

12. In a crankpin grinding machine having a base, a rotatable work support including a pair of spaced work heads on said base to support a crankshaft, a pair of spaced rotatable grinding wheels, an independent fluid operated piston and cylinder to feed each of said wheels simultaneously toward and from a pair of spaced aligned pins on said crankshaft, an independent fluid operated piston and cylinder to traverse each of said wheels simultaneously longitudinally to position the wheels successively into operative position with successive pairs of aligned pins on said shaft, a manually operable valve to control the passage of fluid pressure to said feed cylinder, a manually operable valve to control the passage of fluid under pressure to said traverse cylinders, and a hydraulic interlock to prevent a longitudinal movement of said wheels except when the grinding wheels are in an inoperative position.

13. In a crankpin grinding machine having a base, a rotatable work support thereon, a pair of spaced rotatable grinding wheels, independent means to traverse each of said grinding wheels either independently or simultaneously, an independent piston and cylinder to feed each of said grinding wheels transversely simultaneously to grind a pair of spaced aligned pins on a crankshaft, independent control valves for each of said cylinders, means to actuate said valves either independently or simultaneously, an independent manually operable nut and screw mechanism associated with each of said pistons and cylinders to facilitate adjustment of said grinding wheels relative to said pistons, an independent pawl and ratchet mechanism to actuate each of said nut and screw mechanisms, and electrically actuated means including a solenoid operatively connected to actuate said pawl and ratchet mechanisms either independently or simultaneously.

14. In a crankpin grinding machine having a base, a rotatable work support thereon, a pair of spaced rotatable grinding wheels, independent means to traverse each of said grinding wheels either independently or simultaneously, an independent piston and cylinder to feed each of said grinding wheels transversely simultaneously to grind a pair of spaced aligned pins on a crankshaft, independent control valves for each of said

cylinders, means to actuate said valves either independently or simultaneously, an independent manually operable nut and screw mechanism associated with each of said pistons and cylinders to facilitate adjustment of said grinding wheels relative to said pistons, and electrically actuated means to actuate said nut and screw mechanisms either independently or simultaneously.

15. In a crankpin grinding machine as claimed in claim 14, the combination with the parts and features therein specified, of independent pistons and cylinders independently to actuate each of said pawl and ratchet mechanisms, and electrically actuated valves therefor independently or simultaneously to actuate said pawl and ratchet feeding mechanisms.

16. In a crankpin grinding machine as claimed in claim 14, the combination with the parts and features therein specified, of independent pistons and cylinders independently to actuate each of said pawl and ratchet mechanisms, independent electrically actuated valves therefor for independently actuating said pawl and ratchet feeding mechanisms, and an electrical interconnection including a switch between said electrically actuated valves whereby the valves may operate either independently or simultaneously.

17. In a crankpin grinding machine as claimed in claim 5, the combination with the parts and features therein specified, of a pair of spaced steadyrests each having a frame and an adjustable shoe simultaneously to engage and steady a pair of spaced portions of a work piece, slideways on said frames mating with correspondingly shaped slideways on said base, and connections between the steadyrest frames and the grinding wheels whereby the steadyrests are indexed longitudinally by and in timed relation with the longitudinal indexing movement of the grinding wheels.

18. In a grinding machine as claimed in claim 5, the combination with the parts and features therein specified, of an electric motor to rotate a crankshaft, and an independent electric switch actuated by each of the feed control valves, said switches being connected in parallel and arranged so that movement of both valves to cause a rearward movement of the grinding wheels automatically stops the work drive motor.
